UNITED STATES PATENT OFFICE.

EDWARD C. OMLOR, OF DECATUR, INDIANA.

BARB-WIRE BRACKET FOR FENCEPOSTS.

Application filed May 13, 1925. Serial No. 30,005.

This invention relates to an improved construction in fences and one object of the invention is to provide a fence having guard wires which are preferably formed of barbed wire and extend longitudinally thereof and are disposed above and at opposite sides of its upper edge portion so that horses and other animals will be prevented from reaching over the fence between the fence posts 10 and pushing the fence downwardly a sufficient distance to break the fencing loose from the posts or permit the animals to step over or easily jump the fence.

Another object of the invention is to provide a guard wire carrying bracket which may be readily applied to fence posts formed of angle iron and securely held in place.

Another object of the invention is to so construct the bracket that, when in place, it 20 may be prevented from having movement transversely of the posts.

Another object of the invention is to so construct the brackets that they may be formed from strips of metal bent to the desired shape and, therefore, permit of being 25 very cheaply made.

This invention is illustrated in the accompanying drawing, wherein—

Figure 1 is a sectional view through a fence and showing the fence posts and guard wire bracket in elevation;

Fig. 2 is a view taken at right angles to Fig. 1 and showing a portion of a fence in elevation;

Fig. 3 is a transverse sectional view taken on the line 3—3 of Fig. 1, and

Fig. 4 is a perspective view showing a modified form of guard wire bracket.

The bracket forming the subject matter of this invention is for use in mounting guard wires 1 which are preferably formed of barbed wire and disposed above and upon opposite sides of the fencing 2. The fencing 2 is illustrated as a conventional type 45 of woven wire fencing, and in Figs. 1, 2 and 3 has been shown secured to fence posts, only one of which is illustrated. The post which is indicated by the numeral 3 is formed of angle metal and is disposed with one flange 4 extended parallel to the fencing and its other flange 5 extended from the fencing at right angles to the flange 4. Suitable openings are provided in the flange 4 so that the fencing may be secured to the post 50 by fasteners 6. While a woven wire fencing has been shown, it will be understood that

any other type of fencing could be substituted and further that the fencing may be secured to the post in any desired manner. In Fig. 4, the fencing has been shown connected with a post 7 which is preferably formed of wood and the fencing is secured to this wooden post by the usual staples 8.

The guard wire supporting bracket may be formed, as shown in Figs. 1, 2 and 3 or as shown in Fig. 4. In the construction shown in Figs. 1, 2 and 3, the strip of metal from which the bracket is made has its intermediate portion bent and curved longitudinally to provide a substantially U-shaped head 9. Openings are formed in the end portions of the head and at points in spaced relation longitudinally of the head to receive fasteners 10 which secure the guard wires to the head. While four guard wires have been shown secured to the head, it will be understood that this number may be varied and a larger number or smaller number of wires made use of. By having the wires distributed as shown in Fig. 1, certain of the wires will be disposed above the upper edge of the fencing 2 and others will be disposed upon opposite sides of the fencing in spaced relation thereto and below the upper edge of the fencing. Therefore, horses and other animals will be prevented from reaching over the top of the fencing between the posts and forcing the fencing downwardly so that it is bent out of shape or torn loose from the fence posts. An arrangement of guard wires, such as shown, will also serve very effectively to prevent chickens from climbing upwardly against the wires of a fence forming an enclosure

90 for a chicken yard and jumping over the top of the fence. The end portions of the strip from which the bracket is formed are bent inwardly and upwardly to provide arms 11 which extend to the flange 4 of the post and are then bent downwardly to form shanks 12 adapted to have flat contacting engagement with opposite faces of the flange. The shanks 12 are clamped to the post by plates or strips 13 and 14. The plates extend transversely of the post with their end portions extended beyond the post and joined by bolts 15 which, when tightened, will draw the plates into very firm gripping engagement with the shanks and firmly mount the bracket. The plate or strip 13 has one portion offset to provide a pocket 16 to receive the flange 5 of the post. This

makes it unnecessary to provide a slot in the flange 5 at its junction with the flange 4 and further serves to prevent the strip from having movement transversely of the post. It will, therefore, be seen that the bracket may be very easily and quickly applied to a post and when in place will be firmly mounted and serve to support the guard wires in the desired relation to the fencing.

In Fig. 4, the bracket is somewhat different from the form shown in Figs. 1, 2 and 3. In this construction the strip from which the bracket is formed is bent intermediate its length to provide a head or bridge portion 17 which is straight throughout its length and provided with depending arms 18 which converge downwardly. The head 17 extends transversely across the upper end of the post 7 and is provided with openings to receive the fasteners 10 for the guard wires 2. Openings may also be formed in the depending arms 18 so that guard wires may be secured to the arms at points upon opposite sides of the fencing. The extreme free end portions of the bracket forming strip are bent downwardly, as shown at 19 and constitute feet which will be secured to the fence post by bolts or other fasteners 20. There has, therefore, been provided a bracket which may be very effectively used for supporting guard wires in such a position that they will effectively serve to protect a fence and prevent animals from breaking the fence in endeavoring to reach over or climb the fence.

Having thus described the invention, I claim:

1. In a fence construction, a post, fencing secured to said post, a bracket carried by the upper end portion of said post and formed from a strip bent to provide end portions to engage side faces of the post and an intermediate portion connected with said end portions and adapted to extend across the upper end of the post and downwardly upon the opposite sides of said fencing in spaced relation thereto, guard wires secured to the intermediate portion of said bracket strip and spaced longitudinally thereof with certain of the guard wires disposed below the plane of the upper edge of the fencing, and fastener means securing the end portions of the bracket strip to said post.

2. In a fence construction, a post, fencing secured to said post, a bracket having a head extending transversely above and downwardly upon opposite sides of the upper portion of said fencing in spaced relation thereto, arms extending inwardly and upwardly from the ends of said head and at their in-

ner ends provided with shanks engaging said post, means securing said shanks to said post, and guard wires secured to said head and extending longitudinally of the fencing with certain of the guard wires disposed adjacent the ends of the head and others at points in spaced relation intermediate the ends of the head.

3. In a fence construction, a post, fencing secured to said post, a bracket having a head extending transversely above and downwardly upon opposite sides of the upper portion of said fencing in spaced relation thereto, arms extending inwardly and upwardly from the ends of said head and at their inner ends provided with depending shanks engaging the inner and outer faces of said post, guard wires secured to said head and extending longitudinally of the fencing with certain of the guard wires disposed above the fencing and others at opposite sides of the fencing below the upper edge thereof, and means for securing said shanks to said post.

4. In a fence construction, a post of angle metal, fencing secured to said post against the outer face of one flange thereof, a bracket having a bowed head extending above and upon opposite sides of said fencing with its end portions extending below the plane of the top of the fencing, arms extending inwardly and upwardly from the ends of said head and at their inner ends provided with depending shanks to engage the inner and outer faces of the said flange of said post, guard wires connected with said head and extending longitudinally of the fencing, certain of said guard wires being disposed above the fencing and others at opposite sides of the fencing and below the upper edge thereof, and clamping means for securing said shanks to the said flange of said post.

5. A guard wire bracket comprising a strip of metal bent to provide a longitudinally bowed head portion, and arms extending inwardly and upwardly from its ends, said head portion being provided with longitudinally spaced openings adapted to receive guard wire fasteners, said arms having their free end portions bent to provide shanks adapted to be secured to side faces of a post and support the bracket upon the post with guard wires carried by the bracket disposed above and upon opposite sides of fencing carried by the post, certain of the guard wires at the sides being disposed below the plane of the upper edge of the fencing.

In testimony whereof I affix my signature.
EDWARD C. OMLOR. [L. s.]
